RECESSED DOOR HANDLE

Peter Michalsky, Garfield, N. J.

Application August 3, 1954, Serial No. 447,636

2 Claims. (Cl. 292—336.3)

This invention relates to a recessed handle adapted for use with latches for automobile doors.

An object of this invention is to provide a simple and economical recessed door handle formed from a single piece bar and which bar is inset into a recess in the door.

In one end the bar handle has a square or similar opening which is adapted to be mounted on the rotatable shaft (not shown) of a door latch (not shown) which shaft has an end corresponding in size and shape to the opening in the end of the handle. The said shaft thereby provides a pivotal mounting for the handle so that the free end thereof may move in an arcuate path when the door latch is being released. In this movement of the bar handle it is guided in slots cut in the opposite side walls of a housing through which the handle extends. These slots are weatherstripped with resilient material which will close these slots to prevent dirt, water, etc., from getting inside the door while by its resilient features, the weatherstripping will permit the handle to be moved upwardly and downwardly to operate the door latch.

For a more complete understanding of the invention, reference is made to the following detailed description and accompanying drawing, in which:

Figure 1 is a side elevation view illustrating the latch handle in the recess in the side of a door and

Figure 2 is a transverse cross sectional view in an axial direction with reference to the handle and showing the weatherstripping on one side of the housing.

Referring in detail to the drawing, the numeral 8 designates generally a portion of the outer side of an automobile door or the like having a recessed housing therein. The recessed housing is made by cutting out an essentially rectangular section of the outer door panel at a place located somewhat to the right of the position where there is a square shaft portion (not shown) of a latch (not shown), said square shaft portion being adapted to receive the square aperture 1 in the end of an operating handle 6.

The door panel is cut along two spaced, parallel, horizontal lines of about the same length, the upper line being somewhat to the right of the lower line so that the corners 2, 4 define the shorter diagonal of a somewhat parallelogram-shaped opening.

Extending inwardly toward the inner door panel 11 from the top and bottom of the opening in the outer door panel 8 are parallel top and bottom housing portions, see Fig. 2. These portions extend toward a vertical back wall 5 and are connected to the top and bottom of the vertical back wall 5 by arcuate or rounded corners. This construction, although described as separate pieces, may actually be made as one U-shaped piece, in cross section, and cut off to form ends which are parallel to each other. To these ends there are attached two sides which complete the housing and which sides are provided with somewhat narrow, vertically elongated slots. The handle 6 extends through the housing and is positioned in these vertical slots so as to be movable in a vertical direction in each of these slots. The housing is made of sufficient size to permit a person's hand to reach in through the opening in the outer door panel 8 and grip the handle 6 without interference. The bar handle 6 is shown as

2

being essentially square with rounded corners and at one end there is a square hole 1 for attaching the handle to the square end of a rotary shaft (not shown) of a conventional door latch. The other end 3 of the handle may then move in an arc when the handle 6 is moved to operate the door latch. If desired the handle 6 could be shaped and form-fitting to the gripping parts of a person's hand.

The edges 9 and 10 of the slots in the side walls of the housing may form guides for the handle bar 6 as it moves upwardly and downwardly and these edges may be cushioned and weatherstripped by resilient, rubber-like strips 12, 12. These weatherstrips could be Y-shaped in cross section with the bifurcated portions cemented to opposite sides of the edges 9, 10. The weatherstrips extend toward each other and meet tightly so as to substantially close the elongated slots above and below the handle 6. The resilient features of these weatherstrips 12, 12 will permit the handle 6 to move in up and down directions to operate the latch while at the same time closing the slots in the side walls of the housing to water, dirt, etc.

The bar handle 6 when gripped by the fingers of the hand and pushed downwardly to describe an arc, will transmit this motion through the connecting means 1 to the latch (not shown), after which the handle may be used to pull the door open by moving the door edge 7 away from the door jamb.

I claim:

1. A bar handle formed of a cut off square bar with rounded corners, the length of the bar being predetermined to extend beyond both side walls of a housing into which both ends of the bar handle are adapted to be inset, one end of said bar handle having a square hole for mounting while the other end extends free and goes beyond the other side wall, in combination with a housing having side walls each with an essentially vertical rectangular narrow slot by which the bar handle is guided in up and down movements, said side walls forming the sides for an essentially U-shaped housing which is mounted within the door and at right angles to a parallelogram-shaped opening in the outer door panel and through which the handle bar is accessible to the hand.

2. A bar handle formed of a cut off square bar with rounded corners, the length of the bar being predetermined to extend beyond both side walls of a housing into which both ends of the bar handle are adapted to be inset, one end of said bar handle having a square hole for mounting while the other end extends free and goes beyond the other side wall, in combination with a housing having side walls each with an essentially vertical rectangular narrow slot by which the bar handle is guided in up and down movements, said side walls forming the sides for an essentially U-shaped housing which is mounted within the door and at right angles to a parallelogram-shaped opening in the outer door panel and through which the handle bar is accessible to the hand, said vertical rectangular narrow slots being lined with resilient, cushioning weatherstripping which extends from opposite walls of the slots tightly together and between which the bar handle may move vertically while being cushioned and weatherstripped.
